United States Patent Office.

CHARLES MAGUIRE, OF CHICAGO, ILLINOIS.

Letters Patent No. 92,623, dated July 13, 1869.

COOKING-STOVE.

The Schedule referred to in these Letters Patent and making part of the same.

To all whom it may concern:

Be it known that I, CHARLES MAGUIRE, of Chicago, in the county of Cook, in the State of Illinois, have invented a new and useful Improvement for Ventilating Cook-Stoves; and I do hereby declare that the following is a full and exact description thereof, which will enable those skilled in the art to make and use the same, reference being had to the accompanying drawings, and letters of reference marked thereon, making a part of this specification, in which

Figure 1 is a perspective representation of my invention as applied to a cook-stove.

The nature of the present invention consists in the application of an adjustable covering for a cook-stove, whereby, when culinary work is being done, the smoke and odor, instead of escaping into the room, are carried, by means of a pipe, into the chimney, or flue, said covering having leaves hinged to its lower part, for the convenience of reaching the utensils on the top of the stove, and being arranged, by means of a pulley, to be raised up, when it is not required for use.

A represents a sheet-metal dome, or covering which is suspended over the top of a stove, P, by means of a chain, or rope, L, passing over a pulley, H, and fastening to a looped rod, H'. This rod is attached to the dome at such points as will raise all of its parts evenly, and it projects far enough above an elbow, F, of the escape-pipe, to allow the dome to fit closely down on to the stove.

A pipe, G, is attached to the centre of the dome, A, and extends up into the pipe F, which projects over, and communicates with the pipe E of the stove,

the said pipe F, at its other end, extending into the chimney, in order that the smoke and odor may escape.

Leaves, B, are hinged to the lower edge of the dome A, at D, so that access may be readily had to the utensils on the stove, without raising the ventilator A, and thereby allowing the smoke and odor to escape, hooks and eyes O being used to hold the leaves B up.

A hole, R, is made in the back part of the ventilator, to allow the pipe of the stove to pass through, in order that the dome may cover the rear part of the stove, and at the same time readily rise and lower.

When the ventilator is not required for use, it is raised up out of the way, as shown by dotted lines Z.

In the drawings, the pulley H is represented as attached to a shaft, T, supported by standards V, but in practice it is generally supported by the ceiling of the room.

Having thus described my invention,

What I claim, and desire to secure by Letters Patent of the United States, is—

The dome A, provided with hinged leaves B, an opening, R, to allow the stove-pipe E to pass through, and with pipes G F, to conduct odor and smoke into a chimney, the pipe G being arranged to slide in the vertical part of pipe F, and the dome to raise and lower by means of the looped rod H', pulley H, and chain or rope L, as described.

CHARLES MAGUIRE.
